US00D967827S

(12) **United States Design Patent** (10) Patent No.: **US D967,827 S**
(45) Date of Patent: **** Oct. 25, 2022**

(54) **BACKPLATE FOR AN ELECTRONIC DEVICE**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Daniel W. Jarvis**, Sunnyvale, CA (US); **Duncan Robert Kerr**, San Francisco, CA (US); **Richard H. Koch**, Cupertino, CA (US); **Robert F. Meyer**, Palo Alto, CA (US); **David A. Pakula**, San Francisco, CA (US); **Michael D. Quinones**, Campbell, CA (US); **Peter Russell-Clarke**, San Francisco, CA (US); **Benjamin Andrew Shaffer**, San Jose, CA (US); **Mikael Silvanto**, San Francisco, CA (US); **Ian A. Spraggs**, San Francisco, CA (US); **Sung-Ho Tan**, Vienna (AT); **Clement Tissandier**, San Francisco, CA (US); **Christopher S. Tomasetta**, Sunnyvale, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/822,533**

(22) Filed: **Jan. 10, 2022**

Related U.S. Application Data

(63) Continuation of application No. 29/802,006, filed on Aug. 2, 2021, now Pat. No. Des. 940,722, which is a continuation of application No. 29/761,766, filed on Dec. 11, 2020, now Pat. No. Des. 926,770, which is a continuation of application No. 29/691,337, filed on May 15, 2019, now Pat. No. Des. 905,065.

(57) CLAIM

The ornamental design for a backplate for an electronic device, as shown and described.

DESCRIPTION

FIG. 1 is a bottom front perspective view of a backplate for an electronic device showing the claimed design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the backplate for an electronic device that form no part of the claimed design.

The dot-dash broken lines in the figures show boundaries that form no part of the claimed design.
